UNITED STATES PATENT OFFICE.

WILLIAM G. JOHNSON, OF OKLAHOMA, OKLAHOMA.

RAIL CHAIR AND FASTENER.

1,123,546.

Specification of Letters Patent.

Patented Jan. 5, 1915.

Application filed January 12, 1914. Serial No. 811,711.

To all whom it may concern:

Be it known that I, WILLIAM G. JOHNSON, a citizen of the United States, residing at Oklahoma, in the county of Oklahoma and State of Oklahoma, have invented certain new and useful Improvements in Rail Chairs and Fasteners; and I do declare the following to be a full, clear, and exact description of the invention, such as will enable others skilled in the art to which it appertains to make and use the same.

This invention relates to improvements in rail chairs and fasteners and the primary object of the same is to provide means for securely clamping the chair on the tie as well as clamping the rail in the chair.

A secondary object is to provide a device of this character which will be adjustable to ties of different widths.

With these objects in view, the invention resides in certain novel features of construction and combination as described and claimed and as shown in the drawings wherein—

Figure 1 is a perspective view of my improved rail chair showing its application; Fig. 2 is a plan view thereof; Fig. 3 is a vertical sectional view on line 3—3 of Fig. 2; and Fig. 4 is a detail perspective view of one corner of my rail chair with the rail removed.

In the drawings the numeral 1 designates a railway tie and 2 a rail of ordinary construction and between the two is disposed my improved rail chair and fastener.

My invention, as shown in the drawings, comprises an adjustable bed plate composed of two sliding plates 5 and 6 the plate 5 being notched out at 7 to receive the reduced end 8 of the plate 6, both members 5 and 6 being provided at their outer ends with depending flanges 9 and a plurality of lugs 10 projecting downwardly from said flange and adapted to engage the sides of a tie.

One end of the plate 5 carries a fixed jaw 11 on one end and a stop 12 and a bolt guide 13 on its opposite end for a purpose to appear. The plate 6 is slotted as at 14 at a point under the edge of the rail flange and a pair of fingers 15 incline upwardly from said plate 6 at the edges of the slot 14 and are adapted to overlie the rail 2 when it is in position with the opposite side of its flange resting against a fixed jaw 16 carried by the opposite end of the plate 6.

Slidably mounted within the slot 14 and

between the fingers 15, is a movable jaw 17 which, as shown has its front end bifurcated as at 18 and serrated as at 18' and its rear end beveled as at 19 for a purpose to appear. A bolt guide 20 slotted at one end as at 21 rises from the plate 6 at such a point as to permit the beveled face of a cam head 22 to extend through said slot and contact with the beveled end 19 of the sliding jaw 17. The cam 22 is provided with a stem or bolt 23 which passes through the guide 20 on the plate 6 and the guide 13 on the plate 5 and has a nut 24 threaded on its end. A bolt 25 passes through suitable guides 26 and 27 on the two plates 5 and 6 and is provided with a nut 28. When now the rail is in place as seen in Figs 1. and 2 and the nuts 24 and 28 are tightened on their bolts 23 and 25, it will be seen that the two plates 5 and 6 will be drawn toward each other until the flanges 9 and the lugs 10 come into forcible contact with the sides of the tie. Further tightening of the nut 24 will draw the cam head 22 with its beveled face 19 against the beveled end of the movable jaw 17, thus forcing said jaw into contact with the side of the rail and forcing said rail against the jaws 12 and 16 on the opposite side of the plates where it is securely retained.

I provide the lugs 10 with holes 30 for the reception of spikes 31 in order to more securely fasten the chair on the tie 2. Although it is possible that these spikes could be driven through the plates 5 and 6 into the top of the tie, I prefer to pass them into the sides thereof so that no water may leak in around them and rot the tie.

Although I have described my invention with considerable minuteness, as to details, it will be understood that I do not wish to be limited thereto except as brought out in the appended claims.

What I claim is:

1. The combination with a tie, a rail and a rail stop carried by said tie, of a rail fastener comprising two clamping members adapted to contact with the sides of said tie, bolt guides carried by said clamping members, a movable jaw carried by one of said members and a clamp contacting element adapted to draw said clamp members into engagement with the sides of said tie and to simultaneously project said movable jaw into engagement with said rail.

2. The combination with a tie, a rail car-

ried by said tie, a stop on said tie bearing against one side of said rail, a pair of clamping members adapted to contact with the sides of said tie, bolt guides carried by 5 said clamping members, a guideway in one of said members, a movable jaw within said guideway and a cam headed bolt for drawing the clamp members together and projecting said movable jaw into engagement 10 with said rail.

3. The combination with a tie having a rail mounted thereon, of a rail chair comprising a plurality of bed plates, adjustable transversely of said tie, tie gripping lugs 15 carried by the endmost of said plates, a rigid rail gripping jaw carried by one end of said adjustable chair, an oppositely disposed rail gripping jaw movably carried by the other end of said chair, and means for 20 clamping the flange of said rail between said jaws simultaneously with the gripping of the tie by said tie gripping lugs.

4. A rail chair comprising two bed plates, the innermost end of one plate underlying 25 the innermost end of the opposing plate, depending lugs carried by said bed plates, a fixed jaw carried by one end of said first mentioned bed plate, a stop and a perforated lug carried by the opposite end thereof, a

fixed jaw on one end of said opposing bed 30 plate, a guideway and a slotted lug on the opposite end thereof, a movable jaw in said guideway, a bolt having a cam head contacting with said movable jaw and sliding through said slotted lug and said perforated lug and a nut having a threaded engagement with the end of said bolt. 35

5. The combination with a tie, a rail carried by said tie, a stop on said tie bearing against one side of said rail, a pair of clamping members adapted to contact with the sides of said tie, bolt guides carried by said clamping members, a guideway in one of said members, a movable jaw within said guideway, a cam headed bolt for drawing the clamp members together and projecting said movable jaw into engagement with said rail, and means for securely fastening said clamping members in engagement with the sides of said tie. 40 45 50

In testimony whereof I have hereunto set my hand in presence of two subscribing witnesses.

WILLIAM G. JOHNSON.
